ROCK DRILL

Application filed May 19, 1928. Serial No. 279,027.

This invention relates to rock drills, but more particularly to a fluid actuated rock drill of the type in which the piston or pistons reciprocate independently of the working implement intended to be actuated.

A few of the objects of the invention are to expedite the drilling operation, and to reduce vibration and shock incident to drilling to a minimum.

Other objects will be in part obvious and in part pointed out hereinafter.

In the drawings accompanying the specification and in which similar reference characters refer to similar parts,

Figure 1 is a longitudinal sectional elevation, shown diagrammatically, of a rock drill having a plurality of pistons and showing the pistons in one of their limiting positions,

Figure 2 is a similar view showing the pistons in the other extreme positions, and

Figure 3 is a longitudinal diagrammatic sectional elevation of a rock drill showing a modification of the invention.

Referring to the drawings, and at first more particularly to Figures 1 and 2, A designates a cylinder, B a front head and C a back head of a rock drill. The cylinder A, the front head B and the back head C in this instance comprise the casing parts which may be held in assembled relationship in any suitable manner as for instance by the usual side bolts (not shown).

In accordance with the practice of the invention, the cylinder A has a bore D comprising in this instance a forward reduced portion E and a rearward enlarged portion F. In the enlarged bore F and adjacent the reduced portion E of the bore D is a wall or plate G which divides the bore into forward and rearward piston chambers H and J respectively. The plate G may be maintained securely in position by means of a sleeve K disposed in the enlarged portion F of the bore D to bear with one end against the plate and with its other end against the back head C. The sleeve K may be firmly clamped between the plate G and the back head C or may be secured in position in any suitable manner.

Disposed within the piston chamber J is a piston L having a head O slidably guided by

the sleeve K and a reduced forward extension or stem P which extends slidably through an aperture Q in the plate G and into the piston chamber H to deliver blows of impact to an anvil block R at the front end of the cylinder. In this instance the anvil block R is disposed in a cavity S in the rearward end of the front head B to transmit the blows of the piston L to a working implement T which extends slidably into the front head.

The piston chamber H is likewise provided with a piston. This piston designated by U comprises a head V which lies in the piston chamber H and an extension W which in this instance extends slidably into a bore X in the front end of the cylinder to deliver blows against a head Y of the anvil block R. The piston U has a bore Z which acts as a guiding surface for the stem P of the piston L. The front end of the bore Z in this instance also acts as a guiding surface for a stem b of the anvil block R and against which the extension P of the piston L may strike.

The length of the stem b of the anvil block is determined by the particular type of piston used in the rearward piston chamber J. If a piston without an extension is used, the stem b may of course be of a length to extend into the piston chamber J. Conversely, the extension P of the piston L may be of such length that it may strike directly against the anvil block R, thus omitting the stem b.

The piston chambers H and J are provided with exhaust ports e and d respectively which may lead directly to the atmosphere and are controlled in this instance by the pistons within the respective piston chambers.

For the sake of simplicity of illustration, the drill is shown provided with suitable valve mechanism, as distinguished from integral portions of one or both of the pistons for controlling the admission of pressure fluid into the piston chambers to actuate the pistons. The drill is accordingly provided with a valve chest e having a valve chamber f in which is disposed a distributing valve g of the spool type. The valve g has forward and rearward end heads h and j respectively and an enlarged central flange k adapted to cooperate with inner end surfaces o and p

of bushings *q* and *r* respectively in the valve chest for effecting the distribution of the pressure fluid supplied to the drill through an opening *s* adjacent the innermost ends of the bushings *q* and *r*. Ports *t* and *u* in the valve chest *e* are controlled by the end heads *h* and *j* respectively.

Inasmuch that the particular valve structure forms no part of the present invention and is shown merely as one type of means for effecting the distribution of pressure fluid to the piston chambers, a detailed description thereof is considered unnecessary. Reference is therefore made to only so much of the valve structure as may be helpful in obtaining a clear understanding of the invention and its operation.

Leading from the valve chamber *f* at a point intermediate the opening *s* and the port *u* is an inlet passage *v* which opens at its other end into a passage *w* in the cylinder *A*. The passage *w* has rearward and forward ports *x* and *y* which open into the corresponding ends of the piston chambers *J* and *H*.

In the construction shown the admission of pressure fluid to the contiguous ends of the piston chambers *H* and *J* is effected in this instance through a passage *z* opening into the valve chamber *f* at a point intermediate the opening *s* and the port *t*. The passage *z* has branches 2 and 3 which open into the rearward and forward ends of the piston chambers *H* and *J* respectively.

In drills embodying the present invention and in which the distribution of pressure fluid is controlled by a valve, such as that shown in the drawings, the action or movement of the valve is preferably controlled by the pistons or, as illustrated, by one of the pistons. The cylinder is accordingly provided with crossed kicker passages 4 and 5. The kicker passage 5 opens into the cylinder rearwardly of the exhaust port *d* and at its other end opens into the forward end of the valve chamber *f*. The kicker passage 4 opens with one end into the cylinder at a point forwardly of the exhaust port *d* and communicates at its other end with the rearward end of the valve chamber *f*.

The operation of the device so far described is as follows: With the valve *g* in the forward limiting position and the pistons *L* and *U* in the rearward and forward ends respectively of the piston chambers *J* and *H*, pressure fluid entering the valve chamber *f* rearwardly of the flange *h* will flow through the passages *v* and *w* into the rearward end of the piston chamber *J* and into the front end of the piston chamber *H*.

The introduction of pressure fluid into these ends of the piston chambers will cause the piston *U* to be impelled in a rearwardly direction, and the piston *L* to be impelled forwardly to deliver its blow against the anvil

block *R*. The pistons *L* and *U* will therefore be simultaneously moving in opposite directions so that at the instant the piston *L* delivers its blow against the anvil block *R*, the piston *U* will have reached a position with respect to the plate *G* substantially the same as the piston *L*. This is a preferred arrangement since the jars or vibrations resulting from the impact of the piston *L* against the anvil block will be nullified by the force of the piston *U* against the cushion of air compressed in the rearward end of the piston chamber *H*. However, not all of the air entrapped in the contiguous ends of the piston chambers *H* and *J* during these movements of the pistons will be compressed, as during a portion of the strokes of the pistons the air entrapped in the piston chambers will be expelled through the passages 2, 3 and *z* into the valve chamber *f* and thence through the port *t* to the atmosphere.

During this movement of the pistons, the kicker passage 5 will be uncovered and pressure fluid from the rearward end of the piston chamber *J* will thence flow through the passage 5 into the front end of the valve chamber *f* and act against the front end of the head *h* to throw the valve *g* rearwardly to the position illustrated in Figure 2.

Shortly after the passage 5 has been uncovered, the pistons *L* and *U* will uncover the exhaust ports *d* and *c* to permit the escape of pressure fluid from the piston chambers to the atmosphere.

Upon reversal of the valve *g*, the port *t* will be covered by the head *h* of the valve and the port *u* will be uncovered by the head *j*. In this position of the valve pressure fluid will flow from the opening *s* into the valve chamber *f*, thence through the passages *z*, 2 and 3 into the rearward and front ends of the piston chambers *H* and *J* respectively. The pressure fluid thus admitted will retract the piston *L* to its initial position and will impel the piston *U* forwardly to deliver its blow against the anvil block.

While the pistons are moving in the directions described, the kicker passage 4 will be uncovered by the piston *L* and pressure fluid will thence pass through the kicker passage 4 into the rearward end of the valve chamber *f* to again throw the valve forwardly. As the piston *L* continues in the rearwardly direction and the piston *U* in the forwardly direction, the exhaust ports *d* and *c* will be uncovered by the pistons to permit the escape of pressure fluid from the piston chambers to the atmosphere.

The air compressed in the piston chambers in the ends towards which the pistons are traveling will be expelled through the passages *w* and *v* into the valve chamber *f* from whence it will escape to the atmosphere through the passage *u*.

For the sake of symmetry and simplicity

of illustration, the pistons are arranged coaxially with respect to each other and only two pistons are employed. It will, however, be readily apparent to those skilled in the art that the principle disclosed in the drawings is susceptible of further modification, depending upon the amount of drilling which it is desired to obtain within a given time and other considerations, such as weight and proportions which the work for which the drill is intended will permit.

The advantages of the present invention will be readily apparent to those skilled in the art. Foremost of these advantages are the elimination of vibration which will greatly prolong the life of the drill; the increased number of blows in a given period of time which may be obtained by the use of a plurality of pistons and, the consequent greater footage of drilling than may be obtained by means of drills of the type heretofore employed. These advantageous results may be obtained without constructing the pistons of such proportions and weight as to be detrimental to the elements against which they strike or react.

The modified form of the present invention illustrated in Figure 3 differs from that shown in Figures 1 and 2 in that only a single piston chamber 6 is employed. This piston chamber 6 may, as illustrated, be of uniform diameter throughout its length, and the pistons L and U may be guided directly by the said piston chamber. Due to the fact that only a single piston chamber is employed, the inlet passage z is provided with only one branch 7 which opens into the cylinder at a point intermediate the exhaust ports d and e for driving the piston U forwardly and the piston L in a rearwardly direction. The admission of pressure fluid to the ends of the piston chamber is effected through the passages v and w as in the modification previously described. There is no partition or wall used between the pistons in this instance. The pistons are prevented from striking each other by the air compressed by the pistons as they approach each other.

The operation of this modified form of the invention is in all essential respects like that illustrated in Figures 1 and 2 with the exception, however, that the pressure fluid for driving the piston U forwardly and the piston L rearwardly is admitted directly between the pistons and a portion of the compression formed by the pistons as they approach each other is exhausted through the passages 7 and z into the valve chamber.

The kicker passages 4 and 5 are also controlled by the head O of the piston L and the inlet passages are also preferably so arranged that the pistons will simultaneously move in opposite directions for the reasons hereinbefore set forth.

I claim:

1. A rock drill comprising a cylinder having atmospheric exhaust ports spaced relatively to each other, means in the cylinder between the exhaust ports dividing said cylinder into a plurality of coaxial piston chambers, a piston in each chamber controlling the exhaust ports, means for controlling the distribution of pressure fluid to the chamber, and inlet passages leading from said means to the chambers, one of said passages opening into remote ends of the chambers and another passage opening into contiguous ends of the chambers for causing said pistons to deliver alternate blows to a working implement. 70 75

2. A rock drill comprising a cylinder, a bore therein comprising an enlarged portion and a reduced portion forming a piston chamber, a sleeve in the enlarged portion to form a second piston chamber, a head between the chambers, hammer pistons in the piston chambers, and means for introducing pressure fluid into the piston chambers to cause said pistons to move simultaneously in opposite directions. 80 85 90

In testimony whereof I have signed this specification.

RAYMOND H. SMICKLE.
